(57) **CLAIM**

The ornamental design for a litter guard for an entry opening of a litter device for domestic animals as shown and described.

DESCRIPTION

FIG. 1 is a front perspective view of a litter guard for an entry opening of a litter device for domestic animals;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and

FIG. 9 is a front perspective view thereof, shown in an environment of use;

FIG. 10 is a front perspective view of a litter guard for an entry opening of a litter device for domestic animals according to a second embodiment;

FIG. 11 is a rear perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof; and,

FIG. 18 is a front perspective view thereof, shown in an environment of use.

The broken lines in the figures illustrate portions of the litter guard for an entry opening of a litter device for domestic animals that form no part of the claimed design. The additional broken lines showing a litter device in FIGS. 9 and 18 depict environmental subject matter only that forms no part of the claimed design.
